[57] CLAIM

The ornamental design for a hollow fishing lure, as shown and described.

DESCRIPTION

FIG. 1 is a right side elevational view of a hollow fishing lure, showing my new design, the left side being a mirror image thereof;

FIG. 2 is a front elevational view thereof;

FIG. 3 is a rear elevational view thereof;

FIG. 4 is a top plan view; and

FIG. 5 is a bottom plan view.

FIG. 4

FIG. 2

FIG. 1

FIG. 3

FIG. 5
